UNITED STATES PATENT OFFICE.

THOMAS W. DAVIES, OF ST. LOUIS, MISSOURI, ASSIGNOR TO HIMSELF AND FRANK T. LONG.

SHAFT-TUG.

SPECIFICATION forming part of Letters Patent No. 634,720, dated October 10, 1899.

Application filed July 22, 1898. Serial No. 686,559. (No model.)

To all whom it may concern:

Be it known that I, THOMAS W. DAVIES, a citizen of the United States, residing in St. Louis, Missouri, have invented an Improved 5 Shaft-Tug, of which the following is a specification.

Figure 1 is a perspective of the improved shaft-tug constructed in accordance with the principles of my invention and also including 10 a preferred form of buckle made integral with the tug. Fig. 2 is an outside elevation looking in the direction indicated by the arrow 2 in Fig. 4. Fig. 3 is an inside elevation looking in the direction indicated by the arrow 3 15 in Fig. 4. Fig. 4 is a rear elevation showing the shaft in cross-section and illustrating one style of "hitch up." Figs. 5 and 6 are views analogous to Fig. 4 and showing two other styles of hitch up. Fig. 7 is an elevation of 20 the buckle-tongue.

Referring to the drawings in detail, 8 is the shaft-tug.

9 and 10 are strap-openings at the inner side of the shaft through the band-ring.

25 11 and 12 are the strap-openings at the outer side of the shaft through the shaft-tug.

13 is the box-loop, formed integral with the shaft-tug.

14 is a slot extending from the upper outer 30 strap-opening 11 into the bottom of the box-loop.

15 is a recess in the lower face of the upper wall of the box-loop.

16 is a buckle-tongue having a neck 17 to 35 operate in the slot 14 and the tapered shank 18 to operate in the recess 15. The head 19 is formed upon the opposite end of the neck 17 from the tapered shank 18. The tongue is inserted into its position in the box-loop by 40 passing one of its ends through the strap-opening 11 and then sliding it into the slot 14.

The portion 20 of the shaft-tug which lies 45 between the strap-openings 9 and 10 is offset away from the shaft, as required, to form a recess in which the girth-strap may lie out of contact with the shaft, as shown in Fig. 1 and in dotted lines in Fig. 4.

The ordinary loose hitch up is illustrated 50 in Fig. 1. The lower end of the back-strap 21 and the upper end of the girth 22 are in-

serted through the box-loop. Then the buckle-tongue 16 is inserted through both ends of said straps and then drawn into position, thus securing the straps to the buckle and to the shaft-tug. The girth 22 passes downwardly 55 and inwardly through the strap-opening 9 and then downwardly through the strap-opening 10. This style of hitch up leaves the shaft free to slide through the shaft-tug. The taper of the buckle-tongue causes the back-strap 21 60 to draw upwardly against the lower face of the upper wall of the box-loop, and thereby greatly lessens the strain, which tends to tear the strap. It is found by actual practice that a strap will stand in this position a great deal 65 longer than when secured by an ordinary buckle. In Fig. 4 the girth 22 passes through the strap-opening 9 and then around the shaft and through the strap-opening 10, thus making a very tight and rigid hitch up for fancy 70 driving. In Fig. 5 the girth passes through the strap-opening 9, then over the shaft, and through the strap-opening 12. This will keep the shaft from rattling in the shaft-tug. In Fig. 6 the girth-strap 22 passes through the 75 strap-opening 9, over the shaft, through the strap-opening 11, then back through the strap-opening 12, under the shaft, and through the strap-opening 10.

The hitch up shown in Fig. 1 is suitable for 80 heavy wagons. The hitch up shown in Fig. 5 is suitable for buggies and light wagons. The hitch up shown in Fig. 4 locks the shaft-tug to the shaft and is suitable for light and fancy driving and hitching without hold-backs. The shaft-tug slides back and forth 85 easily on heavy wagons, limits the play when used on light wagons, buggies, or road-carts, and forms a lock or stationary connection with the shaft for driving without breeching. 90

I claim—

As an article of manufacture, a shaft-tug having the strap-openings as 9, 10, 11, 12 adapted to receive the girth as said girth is threaded through the shaft-tug to bind the 95 shaft in position, substantially as described.

THOMAS W. DAVIES.
